PUSH BUTTON DOOR HANDLE

Gerald V. Jakeway, Grand Rapids, Mich., assignor to Keeler Brass Company, Grand Rapids, Mich., a corporation of Michigan

Application February 18, 1955, Serial No. 489,077

5 Claims. (Cl. 292—336.3)

This invention relates to a push button door handle adapted for use on the doors of automobiles, refrigerators and the like.

The main objects of this invention are:

First, to provide a push button door handle adapted for use on doors of automobiles, refrigerators and the like which may be assembled as a unit and installed as such and one in which the parts are so associated to withstand severe usage.

Second, to provide a push button door handle having these advantages in which the parts are simple and economical to produce and may be assembled and disassembled without the aid of tools.

Objects relating to details and economies of the invention will appear from the description to follow. The invention is defined and pointed out in the claims.

A preferred embodiment of the invention is illustrated in the accompanying drawing, in which:

Fig. 1 is a fragmentary view of a door handle embodying my invention mounted upon a door, parts being shown in section longitudinally of the handle.

Fig. 2 is an inside or rear fragmentary view of the handle with the push button stem shown in section.

Fig. 3 is a fragmentary view on a line corresponding to line 3—3 of Fig. 1 showing certain of the structural details.

Fig. 4 is a disassembled or exploded view of the push button, its stem and its biasing spring and the supporting abutment.

In the accompanying drawing 1 represents a door and 2 a panel thereof, the panel having an opening 3 therein adapted to receive a portion of the handle and a second opening 4 adapted to receive an attaching bolt.

The panel 2 is reinforced by the plate 5 having openings therein registering with the openings 3 and 4 and having an angled flange 6 at its front end adapted to receive the attaching screw 7, the door having an opening 8 to permit the introduction and manipulation of the screw. This provision of the reinforcing plate for the panel forms no part of my present invention.

The latch is conventionally illustrated at 9 and is provided with an actuating member 10 also conventionally illustrated.

In the embodiment of my invention illustrated the handle comprises a grip portion 11 and a push button socket 12 formed integrally therewith as a die casting. The grip portion 11 is generally bowed in shape and has an attaching bolt 13 cast therein and adapted to be passed through the panel opening 4 and the reinforcing plate to receive the securing nut 14. The screw 7 is threaded into the bore 15 provided therefore in the handle. This permits the handle being assembled as a unit and attached as a unit.

The push button socket 12 is desirably cylindrical and is provided with an inwardly facing shoulder 16 at its outer end defining an opening 17 in which the push button 18 reciprocates. The push button is desirably formed as a cupped stamping and has an enlarged inner portion 19 providing an outwardly facing shoulder 20 on which the

2

weather sealing and silencing gasket 21 is seated to coact with the inwardly facing shoulder 16 of the socket when the push button is in projected position, as illustrated in Fig. 1.

5 The push button socket is provided at its inner end with circumferentially spaced internal lugs 23 and with internal angularly spaced ribs 22 and terminating at their inner ends in spaced relation to the stops. The enlarged inner end portion 19 of the push button is in sliding engagement with these ribs 22. The combined push button stem guide and abutment member 24 is of such diameter as to be rotatably received within the socket and is provided with peripheral notches 25 adapted to pass the lugs 23 for the inserting or removal of the member 24 when these notches are aligned with the lugs 23.

10 The member 24 is desirably formed as a stamping and the edges of the notches 25 have rib-like upsets 26, the ends 27 of which constitute stops preventing such rotative movement of the member 24 as would disengage it from the lugs except when it is forced axially against the tension of the spring so that the stops 27 will clear the lugs. The member 24 is provided with an outwardly projecting tubular guide 28 for the push button stem 29 which is provided with a disc-like head 30 seated within 15 the push button and preferably of such diameter as to prevent any substantial relative lateral movement of the push button and stem.

20 The coil spring 31 is seated upon and supported by the abutment member 24 and is in biasing thrust engagement with the stem head 30. The spring 31 serves the double function of biasing the push button and releasably holding the member 24 in engagement with the lugs 23 of the socket member. This arrangement permits the very rapid assembly and disassembly of the handle parts without 25 the aid of tools and there are only six parts in the assembling including the sealing and silencing member 21.

25 To assemble the parts the sealing and silencing member 21 is slipped over the push button which is inserted in the socket from the inner side thereof, the stem with the spring thereon is positioned and the abutment and stem guide member is slipped over the projecting end of the stem and inserted into and rotated in the socket until it is brought into position to engage the socket lugs and then released. The spring acts to hold it in that position.

30 The parts cannot be disassembled after the handle is mounted on the door without dismounting the handle from the door. However, when that is done the parts may be readily disassembled should the occasion require. As stated the handle and socket are formed as an integral die casting, and the push button is drawn from sheet stock as is also the abutment member. The parts may be very economically produced and while the structure may be assembled and disassembled without the aid of tools the parts are securely retained in assembled relation.

35 I have illustrated my invention in a practical commercial embodiment thereof. I have not attempted to illustrate other embodiments or adaptations as it is believed that this disclosure will enable those skilled in the art to embody or adapt my invention as may be desired.

40 Having thus described the invention, what is claimed as new and is desired to be secured by Letters Patent is:

45 1. A handle comprising a grip and an open ended socket at the front end of the grip provided with an annular inwardly facing shoulder at its outer end with angularly spaced internal lugs at its inner end, said socket also having angularly spaced longitudinally extending ribs aligned with said lugs, the inner ends of the ribs being spaced from said lugs, a cupped push button having an outwardly offset inner end portion slidably coacting with 50 said ribs and providing an outwardly facing shoulder of a diameter exceeding that of the open outer end of the socket, a push button stem provided with a head at its

outer end of a diameter approximating that of the outer end of the push button and removably seated therein, a removable abutment member rotatable within said socket and having lug engaging portions and peripheral recesses angularly spaced to receive the said angularly spaced lugs of said socket; said abutment having an inwardly projecting rib-like offset at the edges of the recesses constituting stops limiting the rotative movement of the abutment member when it is in engagement with said lugs, said abutment member having a centrally outwardly projecting tubular guide for said push button stem, and a coil spring arranged on said stem and seated on said abutment member with its outer end in thrust engagement with said stem head and acting to bias the push button and to hold the abutment member in engagement with said lugs of said socket.

2. A handle comprising a grip and an open ended socket at the front end of the grip provided with an annular inwardly facing shoulder at its outer end with angularly spaced internal lugs at its inner end, a cupped push button having an outwardly facing shoulder of a diameter exceeding that of the open outer end of the socket, a push button stem provided with a head at its outer end of a diameter approximating that of the outer end of the push button and removably seated therein, a removable abutment member rotatable within said socket and having lug engaging portions and peripheral recesses angularly spaced to receive the said angularly spaced lugs of said socket, said abutment having an inwardly projecting rib-like offset at the edges of the recesses constituting stops limiting the rotative movement of the abutment member when it is in engagement with said lugs, said abutment member having a central guide for said push button stem, and a coil spring arranged on said stem and seated on said abutment member with its outer end in thrust engagement with said stem head and acting to bias the push button and to hold the abutment member in engagement with said lugs of said socket.

3. A handle comprising a grip and an open ended socket at the front end of the grip provided with a push button stop at its outer end with angularly spaced internal lugs at its inner end, a cupped push button having an outwardly facing shoulder of a diameter exceeding that of the open outer end of the socket, a push button stem provided with a head at its outer end fittingly and removably seated in said push button, a removable abutment member rotatable within said socket and having lug engaging portions and peripheral recesses angularly spaced to receive the said angularly spaced lugs of said socket, said abutment having inwardly projecting stops limiting the rotative movement of the abutment member when it is in engagement with said lugs, said abutment member having a central guide for said push button stem,

5 and a coil spring arranged on said stem and seated on said abutment member with its outer end in thrust engagement with said stem head and acting to bias the push button and to hold the abutment member in engagement with said lugs of said socket.

4. A handle comprising a grip and an open ended socket at the front end of the grip provided with angularly spaced internal lugs at its inner end, said socket also having angularly spaced longitudinally extending ribs aligned with said lugs, the inner ends of the ribs being spaced from said lugs, a push button provided with a stem and having an outwardly offset inner end portion slidably coacting with said ribs and providing an outwardly facing shoulder of a diameter exceeding that of the open outer end of the socket, a removable abutment member rotatable within said socket and having lug engaging portions and peripheral recesses angularly spaced to receive the said angularly spaced lugs of said socket, said abutment having inwardly projecting stops limiting its rotative movement when it is in engagement with said lugs, said abutment member having a guide for said push button stem, and a coil spring arranged on said stem and seated on said abutment member with its outer end in thrust engagement with said push button and acting to bias the push button and to hold the abutment member in engagement with said lugs of said socket.

5. A handle comprising a grip and an open ended socket at the front end of the grip provided with angularly spaced internal lugs at its inner end, a push button provided with a stem and having an outwardly facing shoulder of a diameter exceeding that of the open outer end of the socket, a removable abutment member rotatable within said socket and having lug engaging portions and peripheral recesses angularly spaced to receive the said angularly spaced lugs of said socket, said abutment having inwardly projecting stops limiting its rotative movement when it is in engagement with said lugs, said abutment member having a guide for said push button stem; and a coil spring arranged on said stem and seated on said abutment member with its outer end in thrust engagement with said push button and acting to bias the push button and to hold the abutment member in engagement with said lugs of said socket.
